THREAD TENSIONING DEVICE

John A. Williams, Morrisville, Pa., assignor to
 Mitchell-Bissell Co., Trenton, N. J., a corpora-
 tion of New Jersey

Application January 18, 1934, Serial No. 707,164

8 Claims. (Cl. 242—154)

This invention relates to certain improvements in thread tensioning devices for use with textile machinery and particularly to devices of this kind in which the thread is drawn over a friction member as it passes toward the machine, the tension on the thread being varied by changing the extent to which the thread contacts with the surface of said member.

The object of the present invention is to provide a tensioning device of this kind in which the degree of tension on the thread may be readily changed by a simple manipulation of the device by the hand of the operator and without the necessity of employing any tools for that purpose.

A further object is to provide a device of this character in which the extent of contact between the thread and friction member may be readily changed by simply rotating the friction member to any desired position, after which it will be automatically locked in the position to which it is adjusted.

The foregoing and other objects are obtained by the arrangement described in the following specification and illustrated in the accompanying drawing, it being understood that modifications in the details of the device may be resorted to within the scope of the invention.

In said drawing,

Figure 1 is a side view of the device;

Figure 2 is a view of the right hand end of the device showing some of the parts in different positions;

Figure 3 is a view of the left hand end of the device;

Figure 4 is a longitudinal sectional view.

Referring to the drawing in detail, the device in question comprises a friction member 10 which, in the form shown, is made up of an outer tubular portion 10a formed preferably of porcelain or other suitable material and inner bearing portions 10b rigidly secured in the outer portion. The friction member 10 is rotatably mounted on a stationary support or spindle 11 which is rigidly bolted or otherwise suitably secured to a suitable stationary part 12 such as the frame of the machine. A stationary arm 13 extends laterally beyond one end of the friction member 10, the inner end of this arm preferably being rigidly attached to the spindle 11 although it may be attached to any other rigid support. The outer end of the arm 13 carries a stationary thread guide 14 which is positioned laterally of one end of the friction member 10. A movable arm 15 is secured to and extends laterally of the other end of the member 10, and this arm at its

outer end carries a thread guide 16. As the friction member 10 is rotated on its support the position of the arm 15 and thread guide 16 will, of course, be changed as illustrated in Figure 2. The thread indicated at T in Figure 1 is arranged to pass through the guide 16, around the friction member 10, and through the guide 14.

It will be apparent that by changing the position of the arm 15 and guide 16, that is, by rotating it about the axis of the friction member 10, the extent of contact of the thread with the friction member 10 may be increased or decreased and as a result the tension of the thread may be varied. Thus if the member 10 and arm 15 and guide 16 be rotated to the right from the central position indicated in Figure 2 the extent of contact of the thread with the friction member 10 will be decreased and the tension on the thread decreased. Rotation of these parts in the opposite direction will increase the tension of the thread.

To enable the friction member 10, arm 15 and guide 16 to be locked in any desired position of rotary adjustment, one of the bearing portions 10b of said member is provided with a head 17 having a flange or locking member 18 provided with a series of radial notches or depressions 19. The locking member 18 is arranged adjacent the stationary arm 13, which forms a stationary locking member, so that any one of the notches 19 may be engaged over this arm whereby the friction member 10 is locked in position. The friction member 10 is longitudinally movable to a limited extent on the spindle 11, but such longitudinal movement is resisted by a coiled spring 20 surrounding the spindle 11 and bearing at one end against a nut 21, threaded on the spindle, and at the other end against a washer 22 which presses against the end of the friction member 10. This arrangement permits limited movement of the friction member 10 longitudinally of the spindle 11, and such movement permits disengagement of the locking member 18 from the arm 13, and when the parts are thus disengaged, it will be apparent that the friction member 10 may be rotated in either direction to any extent desired.

In operation when it is desired to change the tension on the thread, it is only necessary to grasp the friction member 10 or the arm 15 and draw the same outwardly toward the end of the spindle against the tension of the spring 20. This will disengage the locking member 18 from the arm 13 and the member 10 along with the arm 15, and thread guide 16 may then be swung or ro-

tated in a direction to increase or decrease the extent of contact of the thread with the surface of the friction member and thereby vary the tension on the thread. After the parts are thus rotated to the extent desired one of the notches

5 19 in the spring pressed locking member 18 will engage the arm or locking member 13 to hold the parts in their adjusted position.

It will thus be apparent that the device can be 10 easily and quickly manipulated so that the operator may at any time vary the degree of tension on the threads and this may be done without the use of tools and without interfering with or stopping the passage of the thread toward the 15 machine.

Having thus described the invention, what is claimed as new and desired to be secured by Letters Patent is:

1. A thread tensioning device comprising, in 20 combination, a friction member over which the thread is adapted to be drawn, a stationary thread guide arranged laterally of and adjacent to one end of said member, a movable thread guide arranged laterally of and adjacent to the 25 other end of said member, said last named guide being adjustable in an arc about the axis of said member, and spring pressed locking means rigidly connected to and movable with said last named guide and arranged to lock said guide in any one of a plurality of positions as it is adjusted about the axis of said member.

2. A thread tensioning device comprising, in 30 combination, a friction member over which the thread is adapted to be drawn, a stationary thread guide arranged laterally of and adjacent to one end of said member, an adjustable arm mounted adjacent to and extending laterally of the other end of said member and supported to swing about the axis thereof, a thread guide carried by said arm, and spring pressed locking means rigidly connected to and movable with said arm and arranged to lock said arm in any one of a plurality of positions as the arm is swung about its axis of support.

3. A thread tensioning device comprising, in 40 combination, a friction member over which a thread is adapted to be drawn, a stationary thread guide arranged laterally of and adjacent to one end of said member, an arm arranged adjacent to and extending laterally of the other end of said member, means for supporting said arm for pivotal movement about the axis of said member, a second thread guide carried by said arm, a movable locking member rigidly connected to and 50 movable with said arm as the same is adjusted about its pivotal support, a stationary locking member, interengaging means on said locking members, and a spring for yieldingly holding said locking members in engagement in any desired 55 position of adjustment.

4. In a thread tensioning device, in combination, a friction member over which the thread is adapted to be drawn, a support for said member on which the same is rotatably adjustable, a stationary thread guide arranged adjacent to and laterally of one end of said member, an arm secured to the other end of said member and ex-

tending laterally thereof, a second thread guide carried by said arm, and spring pressed means for locking said member in any one of a plurality of positions as the same is rotatably adjusted on said support.

5. In a thread tensioning device, in combination, a friction member over which a thread is adapted to be drawn, a support on which said member is rotatably mounted to permit adjustment thereof, a stationary thread guide arranged adjacent to and laterally of one end of said friction member, an arm secured to the other end of said friction member and extending laterally thereof, a second thread guide carried by said arm, a movable locking member secured to said friction member, a stationary locking member, interengaging means on said locking members, and a spring for yieldingly holding said locking members in engagement. 10 15

6. In a thread tensioning device, in combination, a friction member over which a thread is adapted to be drawn, a spindle on which said member is rotatably supported to permit adjustment thereof, a stationary thread guide arranged adjacent to and laterally of one end of said member, an arm secured to the other end of said friction member and extending laterally thereof, a thread guide carried by said arm, and spring pressed means for locking said friction member in any one of a plurality of positions as the same 20 25 30 is rotated on said spindle.

7. In a thread tensioning device, in combination, a friction member over which a thread is adapted to be drawn, a spindle on which said member is rotatably supported, a stationary thread guide arranged adjacent to and laterally of one end of said friction member, an arm secured to the other end of said friction member and extending laterally thereof, a thread guide mounted on said arm, a movable locking member carried by and rotatable with said friction member, a stationary locking member cooperating with said movable locking member, said friction member being axially movable on said spindle to effect disengagement of said locking members and permit rotation of said friction member 35 40 45 on said spindle, and a spring opposing said axial movement of said friction member.

8. In a thread tensioning device, in combination, a friction member over which a thread is adapted to be drawn, a stationary spindle on which said member is rotatably supported, an arm secured to said spindle and extending laterally thereof and laterally of one end of said friction member, a thread guide carried by said arm, a second arm secured to the other end of said friction member and extending laterally thereof, a thread guide carried by said second arm, a movable locking member secured to and rotatable with said friction member, said movable locking member having a plurality of notches for engaging said first named arm to hold said friction member in any desired position of adjustment, and a spring for yieldingly holding said locking member in engagement with said first named arm. 50 55 60 65
